UNITED STATES PATENT OFFICE.

CHARLES ALDEN, OF NEWBURG, NEW YORK.

IMPROVED MODE OF EXTINGUISHING FIRES.

Specification forming part of Letters Patent No. 59,156, dated October 30, 1866.

To all whom it may concern:

Be it known that I, CHARLES ALDEN, of Newburg, county of Orange, and State of New York, have invented certain new and useful Improvements in Fire-Proof Buildings and Methods of Extinguishing Fire, of which the following is a full, clear, and exact description, reference being had to the annexed drawings, making part of this specification.

Figure 1 is a horizontal section. Fig. 2 is a vertical cross-section of the same.

Similar letters of reference indicate like parts.

To enable others skilled in the art to make and use my improved fire-proof building and apparatus for extinguishing fire, I will proceed to describe the same in detail.

The nature of my invention consists in constructing a building of fire-proof materials of any kind desired, and the dividing or arranging said building into air-tight compartments, said air-tight compartments being separated by air-spaces, and the arrangement of suitable pipes for exhausting the air from these compartments, forming a vacuum to extinguish fire, and the employment of steam, with suitable arrangement for conveying from these compartments the condensation and surplus steam.

The building is divided into air-tight compartments of any desirable size and form, and is provided with air spaces or flues between or surrounding each compartment, rendering them entirely independent of each other. Connecting with these air-tight chambers and air-flues is a series of pipes, through which steam may be ejected into the chambers to extinguish fires, and through said pipes in the air-spaces the condensation may pass off and the steam escape, if desired. By this arrangement the compartment may be closed and the steam confined therein, or a current of steam passing through until the flames are extinguished.

Connecting with this series of pipes may be arranged an exhaust or air pump, by which the air in these compartments can be exhausted, forming a vacuum for extinguishing fire.

A in the annexed drawings represents a building of any fire-proof material desired, and divided into compartments rendered air-tight in any suitable manner. The doors of these compartments are constructed so as to close air-tight.

The several compartments B are separated from each other, and rendered independent by means of air-spaces C extending from the foundation to the top of the building, and laterally or across the building, forming the floor E of one chamber and the ceiling of the other.

This building may be divided in the center by a passage-way, D, through which freight-wagons may pass to deliver and receive goods or merchandise.

The spaces between the floors and ceiling may be filled with any non-conductor of heat, if preferred.

Through the passage-way D a main pipe, d, is placed, which communicates by means of branch pipes e with the several compartments. Through this pipe D steam may be ejected into all the compartments simultaneously through the branches e, or into any number of the chambers independent of the others.

Each compartment is provided with a waste-pipe, f, through which the condensation of steam may pass off through the air-spaces C. These waste-pipes from the several air-tight compartments connect with a pipe, g, in common, extending the entire height of the building.

In the use of steam for extinguishing fire a constant current may be passed through the compartments, the surplus steam passing up through the outside pipe, g.

In connection with these pipes an air-pump may be so arranged as to exhaust the air from any one or number, or all of these compartments simultaneously, and used as a method of extinguishing fire instead of steam or water.

I do not confine myself to any particular arrangement of pipes and form of building, but have represented a combination here which may be adopted as practical and simple.

Having thus described my invention, I claim as new and desire to secure by Letters Patent—

1. A building composed of a series of airtight compartments, separated from each other by air-spaces or air-chambers, for the purpose specified.

2. The arrangement of pipes *d e f g*, in combination with the air-spaces *C D*, and air-

tight compartments *B*, constructed substantially as described.

The above specification of my invention signed by me this 27th day of September, 1866.

CHARLES ALDEN.
